G. WONSOWICZ

SHADE AND CURTAIN FIXTURE

Filed Nov. 8, 1922

UNITED STATES PATENT OFFICE.

GEORGE WONSOWICZ, OF FORKS, NEW YORK.

SHADE AND CURTAIN FIXTURE.

Application filed November 8, 1922. Serial No. 599,715.

To all whom it may concern:

Be it known that I, GEORGE WONSOWICZ, a citizen of Poland, residing in Forks, in the county of Erie and State of New York, have invented new and useful Improvements in Shade and Curtain Fixtures, of which the following is a specification.

This invention relates to improvements in combination shade and curtain fixtures, and proposes a fixture which is adapted to the support of the shade, the curtain or curtains and the over-drapery.

The object of the invention is to provide a combination fixture by means of which the shade, curtain or curtains and over-drapery will be strongly supported and maintained in the relation necessary to secure good decorative effects, which provides for ready adjustment of the supporting elements whereby to adapt them to shades, curtains or over-drapery of varying widths, and which may be economically produced and readily and securely fitted to the window frame.

With the above objects in view the invention consists generally in novel features of structure and relation, involving the combination of an attachment element which is secured to the window frame, a bracket element carried by the attachment element and adjustable relatively thereto and supporting elements which are carried by the bracket element and adjustable relatively thereto, the construction being such that the supporting elements may be set at any desired position on the bracket element and adjusted as a unit with the latter in relation to the attachment element.

An embodiment of the invention is illustrated in the accompanying drawings, wherein:

Figure 1 is a perspective view of the fixture mounted in position upon a window frame.

Figure 2 is a cross sectional view of the fixture.

Figure 3 is a vertical longitudinal sectional view thereof, taken on line 3—3, Fig. 2.

Figure 4 is a detail sectional view showing the screw for holding the bracket element against movement on the attachment element, and taken on line 4—4, Fig. 3.

Figure 5 is a perspective view of the attachment element.

Figure 6 is a perspective view of the bracket element.

Figure 7 is a perspective view of a supporting arm for co-operation with the supporting rod of the curtain or over-drapery.

Figure 8 is a perspective view of the shade supporting arm.

The fixture includes an attachment element 1 by means of which it is secured to the window frame. The fixture may be duplicated at opposite sides of the window frame or it may be used at only one side of the window frame, in which case the use of fixtures of ordinary form at the other side of the window frame may be assumed. The attachment element 1, in the form shown and preferred, includes a vertical plate 2, which is formed to have a wide and flat bearing against the outer side face of the window frame and which is provided at its ends with angular apertured ears 3 which lie against the front face of the window frame and are secured thereto by screws 4. The plate 2 is formed with an arm 5 which is arranged to project laterally from the window frame and which is preferably flush with the front edge of said plate. The bracket element 6 is mounted on the arm 5 as a support and is adjustable lengthwise of said arm; said bracket element is in the general form of a plate and has projecting from its rear face upper and lower flanges 7 which extend horizontally and are fashioned to engage over the upper and lower edges of the arm 5. By means of the flanges 7 the element 6 is held against the arm 5 but permitted adjustment lengthwise of said arm, the bracket element being held in any desired position to which it may be adjusted by a screw 8 which is threaded through the bracket element and engages the front face of the arm 5, co-operating with the flanges 7 to bind or clamp the bracket element upon the arm 5.

The curtains and over-drapery are supported by the usual rods 9 and 10 as shown in Figure 1. The fixture includes as supporting elements for these rods arms 11 and 12, respectively. These arms are similar in construction but the arm 12 is necessarily longer than the arm 11. The arms 11 and 12 are suitably formed for supporting engagement with the ends of the rods 9 and 10 and preferably are provided with sockets 13, in which the adjacent ends of the rods 110

9 and 10 are fitted. The arms 11 and 12 are carried by the bracket element 6 and are preferably adjustable relatively to one another and to said element.

- 5 The ends of the arms 11 and 12 remote from the sockets 13 are slidably fitted to the plate 6 in any suitable manner. As shown and preferred the plate 6 is provided at the front thereof with upper and lower horizontal flanges 14 having inwardly directed extensions 15 and the arms 11 and 12 are formed with substantially T-shaped extensions 16 which fit conformably and slidably between the flanges 14 and the extensions 15 thereof.
- 10 The arms 11 and 12 may be set at any desired positions relatively to one another and the plate 6, and are held against displacement by suitable means, preferably consisting of securing screws 17 threaded through the lower extension 15. The extension 16 may be provided with longitudinal grooves 18 in which the ends of the screws 17 engage. The arms 11 and 12, as secured by the screws 17, have a firm bearing, by means of their extensions 16, against the plate 6.

The fixture is completed by the arm 19 for the support of the shade roller, the roller engaging end of this arm being formed with the usual open recess 20 to receive the supporting projection at the end of the roller. The arm 19 is adjustably supported by the plate 6, preferably by means of a threaded horizontal rod 21 journalled in bearings 22 provided at the ends and below the body of the plate 6. The arm 19 is provided with a threaded opening in which the rod 21 engages and is formed in its upper face with a groove 23 to take over a guiding and supporting rib 24 provided along the lower edge of the plate 6. The rod 21 has at one end a knurled finger piece 25 by which it may be turned, thereby to adjust the arm 19 to any position desired.

In the application of the fixture, the attachment element 1 is first secured to the window frame, the plate 6 is then slipped over the arm 5 to a desired extent and se-

cured by the screw 8 and the arms 12, 13 and 19 are adjusted to the positions required for their support of the rods 9 and 10 and the shade roller respectively, the arms 12 and 13 being secured by the screws 17 and the arm 19 remaining fast in the position to which it is adjusted. When the removal of the supporting arms is required this may be accomplished merely by removing the plate 6 from the arm 5 without disturbing the adjustment of the supporting arms relatively to one another and to said plate. In like manner, once the adjustment of the supporting arms has been made the arms may be replaced in their operative positions merely by replacing the plate 6 upon the arm 5 and shifting it to the position in which the supporting arms 11, 12 and 19 are engaged with the parts which they are to support.

The adjusting screw 21 is capable of turning in the bearings 22 but is held against lengthwise motion therein, this being preferably accomplished by engaging the finger piece 26 with the outer side of one bearing lug 22 and providing this screw with a cotter pin 26.

Having described my invention, I claim:

In a fixture of the type described, an attachment element having means for securement to a window frame and an arm arranged to project laterally from said frame, a plate having horizontal angular flanges projecting from its rear face and forming an undercut rear guideway which receives said arm, said plate being thereby lengthwise adjustable upon and removable from said arm, said plate also having horizontal angular flanges projecting from its front face and forming an undercut front guideway, independent supporting arms having enlarged extensions conformably and slidably engaging with the guideway between said last named flanges, and securing screws on said plate for holding said plate and supporting arms against movement from positions to which they may be adjusted.

GEORGE WONSOWICZ.
